UNITED STATES PATENT OFFICE.

THOMAS OTTIGNON, OF WEXFORD, ONTARIO, CANADA.

FIRE-ESCAPE.

1,092,662.

Specification of Letters Patent.

Patented Apr. 7, 1914.

Application filed February 26, 1913. Serial No. 750,728.

To all whom it may concern:

Be it known that I, THOMAS OTTIGNON, a subject of the King of Great Britain, and resident of the town of Wexford, in the 5 county of York, in the Province of Ontario, in the Dominion of Canada, have invented certain new and useful Improvements in Fire-Escapes, of which the following is a full specification.

10 This invention relates to fire escapes particularly adapted to be installed in a building when the same is erected but which may be put in any building at any time without altering the architecture of the same; the fire 15 escape being in the interior of the said building.

The objects of the invention are to provide a fire escape which will be always ready 20 to be used without any preparation having to be made previous to its use and which will effect the speedy transit of a large number of persons from any floor in the building to the ground.

A further object is to provide for the fire 25 proof isolation of the escape in such manner that fire will be prevented from reaching the same while ready access can be obtained to the fire escape from any floor.

Still further objects are to provide upholstered protecting means for the reception of 30 persons at the lower floor so as to prevent injury to them owing to the velocity at which they may travel down the fire escape and also to arrange for the opening of a suitable 35 smoke door in the upper part of the building to allow smoke to escape from the isolated fire escape should it gain access thereto, the said smoke door being adapted to be opened from any floor.

40 This invention consists essentially of the novel construction and arrangement of chutes, the said chutes being situated between each floor of the building and divided off from the main part of the building by 45 means of fire proof walls of any suitable construction, the said walls having doors therein upon each floor whereby communication is established between the main part of the building and the fire escape.

50 Means are provided at the lower end of each chute whereby persons may arrest their progress sufficiently to enable them to reverse their position before proceeding down the next chute which slopes in the reverse 55 direction. Openings are also provided at the

lower end walls of each chute so that persons may enter the same from any floor.

The uppermost floor has a door in the wall or roof, leading to the outer air, which door is arranged to be opened from any floor by 60 pulling a chain, cord or the like, for the purpose of allowing smoke to escape.

The lower end of the chute upon the ground floor has an upholstered extension which is adapted to lie along the ground in 65 front of the chute when in position for use, and prevents the liability of anyone being injured owing to the velocity with which they are projected from the chute all of which is more particularly described and 70 shown in the accompanying specification and drawings in which—

Figure 1 is a sectional diagrammatic view of the building showing the improved fire escape installed therein part of the fire proof 75 wall being broken away to better illustrate the construction of the device. Fig. 2 is a sectional view of the same on the line *a—b* Fig. 1. Fig. 3 is a sectional view of the same on the line *c—d* Fig. 1. Fig. 4 is a 80 perspective view of the arresting means at the lower end of the chute on the ground floor.

Similar characters of reference indicate 85 similar parts in the several figures of the drawings.

A is the isolated part of the building which is divided from the main part B of the said building by the fire proof wall C which is shown in Fig. 1, and broken away 90 in order that the arrangement of the chutes within the isolated part A of the building may be clearly illustrated. The fire proof wall C has doors therein opening on to each of the floors of the building in order that access may be had to the isolated part A of the building from the main part B when it is desired to use the fire escape in cases of emergency or the like. The fire escape proper consists of a series of chutes leading 95 to the ground floor, or to any other such floor as may be desired from which escape from the building may be effected in cases of emergency. These chutes are marked upon the drawing 1, 2 and 3 respectively. The chute 1 extends in an inclined direction from the floor of the top flat having an opening therein surrounded by suitable upholstered means whereby a person may enter the upper end of the chute 1. The lower 100 105 110

end of the chute 1 is immediately above the upper end of the chute 2 which chute 2 slopes in the opposite direction to the said chute 1, communication being established between the two chutes by means of an opening in the floor at the lower end of the said chute 1, and means provided at the lower end of the said chute 1 whereby the chute 2 may be entered at this point if desired. The chute 2 also communicates at its lower end with the farther chute 3 in a similar manner to that in which the chute 1 communicates with the said chute 2, the said chute 3 sloping in the opposite direction to the chute 2 as illustrated in Fig. 1 of the drawing. This arrangement of chutes sloping in opposite directions alternately is continued until the ground floor is reached, or other such floor from which escape from the building may be effected.

As illustrated in the drawing the number of chutes may be increased in the lower floors of the building in order to accommodate the increasing number of persons who may be using the fire escape in cases of fire, but of course this depends entirely upon the capacity of the building, and it may only be necessary to make the series of chutes single throughout. Suitable pillars or the like, 5 and 6 may be used at different points under the chutes in order to strengthen and support same.

At the lower end of each of the chutes 1 and 2 are arranged arresting means 7 which arresting means preferably consists of a wooden bar 7^a or the like suspended above the opening in the floor communicating with the next chute in order that persons sliding down one chute may seize the said bar and arrest their progress sufficiently long to enable them to turn around before proceeding down the oppositely inclined chute beneath them. The walls surrounding the lower ends of the said chute are upholstered in order to prevent injury to any person by reason of their coming in contact with the said walls at the lower ends of the chutes. The chutes are cut away at their lower ends as indicated in 9 and 10 in order that a person may enter the chute from any floor.

The uppermost floor of the building is provided with a door 11, or the like, which door 11 communicates with the outer air and is provided with a bolt 12 adapted to be operated from any floor of the building by means of a rope, chain, or the like 13 suitably communicated with the said bolt 12. By this means the said door 11 may be opened by pulling the rope, chain or the like 13 from any floor for the purpose of allowing smoke, which may have gained access to the isolated portion of the building to escape. Instead of a door 11 as illustrated in the drawing, any suitable form of ventilation or the like may be used in the upper flat of the

building, and may be in either the wall or the roof thereof.

The lower end of the chute or chutes upon the ground floor are provided with means for preventing liability of any one being injured owing to the velocity with which they are projected from the said chute or chutes, the said means consisting of an upholstered extension 14 hinged at its middle and adapted to be turned upward when the fire escape is not in use. The said upholstered extension 14, is intended to project beyond the door of the building when in use and is for effecting the moving of the said extension 14 to this position when the door 15 forming the exit from the building is opened. To effect this, the extension 14 is provided with a member 16, which extends forwardly and rearwardly of the said extension 14, the front end of the said member 16 bearing against the lower part of the door 15 when the said door 15 is closed. The rearwardly extending part of the member 16, is slidably held within the long tubular or box like member 17 upon the floor of the building, and bears against the spring 18 and the upwardly turned part will fall and lie outside of the building. Persons descending down the lowermost chute will be arrested by said extension 14 outside of the building, the said extension 14 being heavily upholstered and preventing injury to such persons owing to the velocity with which they are projecting from the chute or chutes. In cases where the chutes are arranged to slope at an angle which is not very great and the velocity at which a person travels down the same is normal, the extension 14 may be dispensed with.

It will be readily understood that the installing of a fire escape of this type within a building does not necessitate the altering of the architecture of the same, except for the fire proof wall which effects the isolating of that part of the building from the main part. This fire escape is also ready for use at all times without any preparation and the chutes 1 and 2 may be either upholstered or provided with smooth canvas troughs, or troughs of other material as may be desired. The speed at which a person travels down the said chutes may be regulated by the persons themselves grasping the sides of the said chutes when using the same, or suitable rails may be provided upon the said chutes for a similar purpose.

It will be obvious that this fire escape is protected from the fire, and at the same time a number of people may be congregated around the entrances of the different chutes while being isolated from that part of the building which is on fire. Further, where the number of chutes is increased at the lower floors, persons upon those floors may enter the chutes without interfering with the progress of other persons coming down

the chutes from the upper floors by which congestion may be avoided.

The fire proof wall may be of any suitable construction, the doors of the same also being fire proof, and the doors upon each floor being arranged immediately opposite the lower end of the chute upon that floor.

Owing to the upholstered nature of the chutes a person is not liable to be injured during progress down same, even if the said person does not take advantage of the arresting means at the bottom in order to turn themselves around before proceeding down the next chute. The angles at which the chutes are arranged may vary in different cases, and under different circumstances.

This invention may be developed within the scope of the following claim without departing from the essential features of the same, and it is desired that the specification and drawings be read as being merely illustrative, and not in a limiting sense except as necessitated by the prior art.

What I claim as my invention is.

In a fire escape, a combination of inclined chutes the lower most of which is provided with a movable extension at its lower end, said extension comprising a hinged upholstered member, the front part of which is adapted to be turned up when the fire escape is not in use, a forward and rearwardly extending member fixed to said extension, and resilient means tending to force the said extension toward said chute, a tubular bar in which said rearwardly extending member is slidably fixed and a spring within said bar tending to force the said rearwardly extending member outward.

Signed at the city of Toronto, in the county of York, in the Province of Ontario, in the Dominion of Canada, this 3rd day of February 1913.

THOMAS OTTIGNON.
